(57) **CLAIM**

The ornamental design for an electrically connective bracelet clasp, as shown and described.

DESCRIPTION

FIG. 1 is an upper perspective view of the electrically connective bracelet clasp of the present invention showing my new design, the clasp being in a connected configuration; FIG. 2 is a top view of the electrically connective bracelet clasp in the connected configuration;

FIG. 3 is a front elevational view of the electrically connective bracelet clasp in the connected configuration; FIG. 4 is a rear elevational view of the electrically connective bracelet clasp in the connected configuration; FIG. 5 is a first end view of the electrically connective bracelet clasp;

FIG. 6 is a second end view of the electrically connective bracelet clasp, the second end view being opposite the first end view;

FIG. 7 is a bottom view of the electrically connective bracelet clasp in the connected configuration;

FIG. 8 is an upper perspective view of the electrically connective bracelet clasp in a disconnected configuration;

FIG. 9 is a lower perspective view of the electrically connective bracelet clasp in the disconnected configuration; FIG. 10 is a top view of the electrically connective bracelet clasp in the disconnected configuration;

FIG. 11 is a front elevational view of the electrically connective bracelet clasp in the disconnected configuration; FIG. 12 is a bottom view of the electrically connective bracelet clasp in the disconnected configuration; and,

FIG. 13 is a rear elevational view of the electrically connective bracelet clasp in the disconnected configuration.

The broken lines in the drawings illustrate portions of the electrically connective bracelet clasp and a corresponding bracelet band that form no part of the claimed design.
